UNITED STATES PATENT OFFICE.

ERNEST L. ETHERIDGE, OF BROOKLYN, NEW YORK.

WASHING MACHINE.

Application filed May 18, 1922. Serial No. 561,926.

To all whom it may concern:

Be it known that I, ERNEST L. ETHERIDGE, a citizen of the United States, and resident of the city of New York, borough 5 of Brooklyn, county of Kings, and State of New York, have invented a new and Improved Washing Machine, of which the following is a full, clear, and exact description.

10 My invention relates to a washing machine, and aims to provide a device of this nature particularly adapted for home use, although it is not necessarily limited to this particular association.

15 It is an object of the present invention to provide a device of the character stated which may be associated with a conventional laundry tub, such as forms a part 20 of the standard equipment of laundry rooms.

It is a further object of the present invention to provide a washing machine embodying extremely simple construction capable 25 of being placed upon the market at a nominal figure, and further providing a construction involving a minimum of mechanical difficulties and complications.

A still further object of my present invention is that of constructing a washing 30 machine including a plurality of parts which when not in use may be completely stored within and housed by the conventional tub aforementioned so that no unsightly appearance will be presented.

35 With these and further objects in mind the present invention has reference to a washing machine including a body adapted to extend into a tub, together with means serving to support this body and permitting 40 of an operation thereof.

Reference is had to the attached sheets of drawings, as illustrating one practical embodiment of my invention, and it will be seen that;

45 Figure 1 is a sectional side view of a tub of conventional construction and showing my improved washing machine associated therewith.

50 Figure 2 is a transverse sectional view of the tub, and showing the parts of the washing machine stored therein.

Figure 3 is a sectional view taken along the line 3-3 and in the direction of the arrows indicated in Figure 1, and

55 Figure 4 is a sectional view taken along

the line 4-4 and also in the direction of the arrows indicated in Figure 1.

It will be seen in these various views that the reference numeral 5 indicates a conventional tub with which a lid 6 is associated 60 in the usual manner, by means of hinges, and positioned within this tub is my improved type of washing machine supported therein in a manner hereinafter described.

Referring to the machine proper it will 65 be seen that the same preferably includes a pair of perforated end disks 7, which mount, adjacent their edge portions, a series of rods 8, thus forming a cage. A section 9 of each of the disks 7 is movable with 70 respect to the body, and attached thereto by any suitable means, such as a hinge, 10, it being noted that each of the sections 9 is normally retained in its proper position by a suitable catch 11. 75

In view of the fact that each of the sections 9 carries rods 8 forming a continuation 80 of the annular series of rods supported between the disks 7, it will be understood that upon the catches 11 being loosened the sections 9 together with the rods carried thereby may be swung outwardly, and this portion of the device will thus serve as a door whereby access may be had into the interior of the cage formed by the remaining rods 8 attached to the disks 7. 85

Now with a view of supporting the washing machine within the tub, it will be noted, as has been shown in Figure 1, that a bracket 12 is hooked over the edge of the tub, and is secured in this position by any suitable means, such as a set screw 13. The upper end of this bracket terminates in a platform 14 suitable for the mounting of a motor 15, and the lower end of the bracket terminates 90 in a sleeve 16 adapted to rotatably house a shaft 17, a detachment of this shaft from the sleeve being normally prevented by virtue of a screw 18 associated with the latter, and extending into a groove 19 provided in the former. It is obvious, in that connection, that by virtue of the screw, the shaft 17 may 95 also be entirely detached from the sleeve 16 for a purpose hereinafter brought out. The shaft 17 has secured thereto at the end 100 of the sleeve 16 a gear 20, the teeth of which are capable of meshing with the teeth of a gear 21 attached to the shaft of the motor 15. The gear 20 may be secured to the shaft in any suitable manner, as by a set screw (not 110

shown) extending through the hub of the gear and engaging the shaft.

Thus when the motor 15 is operated it will be apparent that the gear 20 is also rotated, and by virtue of the fact that the latter is affixed to the shaft 17, a corresponding movement on the part of this member will result. It is also to be noted that the disk 7 arranged adjacent to the shaft 17 is formed 10 with a squared opening surrounded by the flange 22, and the end of the shaft 17 terminates in a squared portion 23 corresponding to this opening. Thus incident to the fact that the shaft 17 is turned, and further 15 due to the fact that the part 23 thereof keys into the opening surrounded by the flange 22, it will be understood that the rotation aforementioned, which is imparted to the shaft, will cause a turning of the body of 20 the washing machine, assuming that the second end of the same is also rotatably supported. This latter support may be effected in any suitable manner such as by the provision of an adjustable bracket 24, bridging 25 the edge of the tub 5, at a point diametrically opposite from the point at which the bracket 12 is positioned, this bracket 24 presenting a bearing 25 into which a shaft 26 carried by the second disk 7 is adapted to 30 extend.

Thus in operation the parts of the machine are disposed in the manner shown in Figures 1, 3 and 4 in which the entire device is supported by the tub, and in which the 35 machine is driven by the mechanism illustrated. It will be obvious that in this instance, the body of the machine may be filled with clothes to be washed, through the door provided by the sections 9 subsequent to 40 which these sections are moved to their seated position, i. e. the position shown in Figures 1, 3 and 4, and after which the machine is rotated within the body of the tub, which latter is preferably filled with a 45 mixture of soap and water. This operation of the parts will obviously result in the clothes being cleansed, and the same may be removed when this result has been achieved. However upon it being desired to store the 50 machine this may be accomplished by simply

disengaging the brackets 12 and 24 from the tub 5, and at the same time detaching the hinged fasteners 10, and the securing members 11 so that the sections 9, together with the parts associated therewith may be removed from the body of the tub. These latter parts may be disposed within the said body, and the same is also true of the brackets, shafts, etc. it being noted, however, that all of the parts of the machine when disposed in this manner, occupy a space which will permit of the lid associated with the tub being closed. This result is to be predicated to the fact that the sections 9 are removable, and thus upon the same being detached from the body of the machine, the space between opposite edges of the disks is materially decreased, and I am thereby enabled to associate a washing machine having a relatively large body, with the tub.

Thus all of the objects of this invention have been accomplished, and it will further be understood that numerous modifications of structure might readily be resorted to without in the least departing from the scope 70 of my claim; which is;

In a washing machine, brackets adapted for attachment to opposite sides of a tub and having portions depending into said tub, the depending portion of one of said brackets 80 having a laterally extending bearing sleeve, a shaft having one end mounted in said sleeve and its other end projecting beyond the same, the portion of the shaft within said bearing having an annular groove, 85 means extending through said bearing and engageable in said groove to prevent longitudinal movement of the shaft within said sleeve, said means being removable to permit of detaching the shaft from said bearing, a 90 rotatable body supported by the depending portions of said brackets and having one of its end members connected to the portion of said shaft projecting beyond said bearing, a gear secured to said shaft and interposed between said end member and the adjacent end of said bearing, and means supported by one of said brackets for rotating 95 said gear.

ERNEST L. ETHERIDGE.
